ROTARY SIFTER TOP

Ted M. Ekstrom, Rockford, Ill., assignor to J. L. Clark Manufacturing Co., Rockford, Ill., a corporation of Illinois

Application July 17, 1944, Serial No. 545,343

2 Claims. (Cl. 222—548)

1

This invention relates to sifter tops for enabling powdered material to be dispensed from a container, and has more particular reference to tops having an inverted cup which is turned to open and close holes through which the material is sifted.

One object is to provide a top of the above character which is of simple and inexpensive construction, which may be assembled readily, and which presents a smooth external surface free from indentations or projections.

Another object is to provide a sifter top comprising two inverted nested cups having novel means formed thereon for holding the cups in assembled relation and limiting their relative turning movements.

The invention also resides in the novel structural character of the stops and guides which facilitates assembly and avoids binding between the two cups.

Other objects and advantages of the invention will become apparent from the following detailed description taken in connection with the accompanying drawings, in which

Figure 1 is a fragmentary perspective view of the upper portion of a powder container having a top embodying the novel features of the present invention.

Fig. 2 is an exploded perspective view.

Fig. 3 is a vertical diametrical sectional view.

Figs. 4 and 5 are sections taken respectively along the lines 4—4 and 5—5 of Fig. 3.

While the invention is susceptible of various modifications and alternative constructions, I have shown in the drawings and will herein describe in detail the preferred embodiment. It is to be understood, however, that I do not intend to limit the invention by such disclosure, but aim to cover all modifications and alternative constructions falling within the spirit and scope of the invention as expressed in the appended claims.

In the drawings, the invention is embodied in a sifter top 6 upstanding from and smaller than a container 7 which may be made of sheet metal and, if desired, of non-circular cross section. The top proper comprises two inverted cups 8 and 9 nested together and adapted for rotation of the outer cup 8 about the container axis. The flattened bottom 10 of the outer cup lies tightly against an annular portion 11 in the bottom of the inner cup 9, and these portions are formed with annular rows of equally spaced holes 12 and 13 which may be brought into and out of registry by turning the outer cup. The side walls 14

2

and 15 of the cups are cylindrical, and the open end lip of the inner cup has an outturned flange 16 interlocked with the inner peripheral margin of an inturned flange 17 at the upper end of the container body, the latter and the inner cup being thereby made rigid with each other.

In accordance with the present invention, the outer cup is held down against the inner cup, and its turning is limited by novel guide and stop elements, the coating parts of which are formed inside and at the lower edge or lip of the outer cup and on the exterior of the inner cup so as to leave the external surface of the outer cup smooth and of artistic appearance. Herein, the guide comprises an external projection in the form of an annular bead 18 of rounded cross section projecting outwardly from the side wall 15 of the inner cup and formed from the metal thereof in a plane perpendicular to the cup axis and spaced above the flange 16 and the lower end of the outer cup wall 14. Preferably, the bead is divided as shown into a plurality of parts spaced apart circumferentially. The lower edge or lip of the cup wall 14 is formed with an inturned flange by rolling metal inwardly and then upwardly to form a curl 19 smaller in diameter than the bead 18 and underlying and contacting the latter so that the outer cup bottom 10 is held down against the inner cup while at the same time permitting turning of the outer cup by sliding of the curl 19 along the bead 18. Preferably, the curl is interrupted and divided into a plurality, three in the present instance, of arcs which herein are about half the length of the arcuate spaces intervening between them. Around the cut-away portions of the curl, the side wall 14 of the outer cup is preferably turned in slightly as indicated at 20.

To limit the angular turning of the outer cup, the ends 21 of the curls or inturned flanges 19 cooperate with stops formed out of the metal of the inner cup wall 15 and comprising herein annularly spaced vertical ribs 22 extending parallel to the container axis between the adjacent ends of the horizontal beads 18. Thus, when the parts are assembled, the outer cup may be turned in one direction until one of the extreme abrupt ends 21 of the curls comes against one side of the stop ribs 22. Turning in the opposite direction is limited by engagement of the other ends 21 of the curls with the other sides of the ribs 22. The lengths and angular spacing of the curls and ribs 22 are correlated with the spacing of the sifter holes 12 and 13 so that in one limit position, these holes are in full registry thereby per-

mitting the container contents to be sifted out. In the other limit position, the holes of the inner cup are completely covered.

To facilitate assembly of the top, the stop ribs 22 are preferably extended above the beads 18. Thus, when the outer cup is placed down over the inner cup and simultaneously turned, the curls 19 will always enter between the stop ribs 22, thereby establishing a correct angular relation between the two cups. In a production line an outer cup is first loosely nested over the inner cup and twisted slightly until the inwardly turned flanges 19 fall between the upwardly extending portions of the stops 22. Then, as the inner cup is forced down, the curls 19 ride over and then contract beneath the guide beads 18. It will be apparent that the curls will fit between any pair of the stop ribs 22.

Since the lip of the outer cup is spread to form the spaced curls 19, it is relatively yieldable so as to relieve any tendency of the two cups to bind, thereby facilitating turning of the outer cup at all times. The interengaging lugs which coact to hold the cups nested and to limit the turning of the outer cup are, it will be observed, formed by the lower inturned edge of the outer cup and on the exterior of the inner cup so that the necessity of forming depressions or projections in the exterior of the outer cup is avoided. Accordingly, the assembled top when composed of sheet metal parts has a smooth external surface and, therefore, presents a neat and artistic appearance.

I claim as my invention:

1. A sifter top comprising an outer cup having an arcuate inturned flange extending partially around the peripheral edge of the open cup so that the cup presents a smooth continuous outer side surface and peripheral edge, an inner cup nested into said outer cup against the end wall thereof, an external circumferentially extending projection on the side wall of said inner cup overlying said flange for sliding engagement therewith to hold the cups nested while permitting turning of the outer cup, external stops on the side wall of the inner cup angularly spaced farther apart than the circumferential length of said flange and extending parallel to the axis of the cup on

both sides of said projection for receiving said flange between them whereby to locate the cups angularly relative to each other during initial nesting thereof and also to limit turning of the outer cup in either direction, and means on the engaging end walls of said cups defining perforations which register with each other when said flange abuts one of said stops and which are out of register when the flange abuts against the other stop.

2. A sifter top comprising an outer cup having an arcuate inturned flange extending partially around the peripheral edge of the open cup end and curled inwardly and toward the cup bottom so that the cup presents a smooth continuous outer side surface and peripheral edge, said flange being of uniform cross section throughout its circumferential length and terminating in abrupt radially disposed ends facing away from each other, an inner cup nested into said outer cup against the end thereof, an external projection on the side wall of said inner cup overlying said flange for sliding engagement therewith to hold the cups nested while permitting turning of the outer cup, external stops on the side wall of the inner cup angularly spaced farther apart than the length of said flange and extending along the axis of the cup for engagement with said flange ends to limit turning of the outer cup in either direction, and means on the engaging end walls of said cups defining perforations which register with each other when said flange abuts one of said stops and which are out of register when the flange abuts against the other stop.

TED M. EKSTROM.
